PAGE 2

Fig. 2.

Fig. 3.

Fig. 4

Fig. 5

Fig. 1 is a front perspective view of a clock embodying my new design with the front cover in an open position;

Fig. 2 is a front perspective view of the clock shown in Fig. 1 with the front cover in a closed position;

Fig. 3 is a side elevational view of the clock shown in Fig. 1 with the cover in a closed position;

Fig. 4 is a front elevational view of the clock shown in Fig. 1 with the front cover in a closed position;

Fig. 5 is a top plan view of the clock shown in Fig. 1 with the cover in a closed position.

I claim:

The ornamental design for a clock or similar article, substantially as shown.
